UNITED STATES PATENT OFFICE

CHARLES LOFMAN, OF CHICAGO, ILLINOIS, ASSIGNOR TO S. KARPEN & BROS., A CORPORATION OF ILLINOIS

DESIGN FOR A TEXTILE PANEL FOR A MATTRESS COVER

Application filed April 28, 1931. Serial No. 39,645. Term of patent 3½ years.

To all whom it may concern:

Be it known that I, CHARLES LOFMAN, a citizen of the United States, residing at Chicago, Cook County, Illinois, have invented a new, original, and ornamental Design for Textile Panel for a Mattress Cover, of which the following is a specification, reference being had to the accompanying drawing, forming a part thereof.

The figure of the drawing is a plan view of a textile panel for a mattress cover showing approximately one-fourth of my design in detail, the dotted lines outlining the extension of the detailed design in the other three corners in proper relation thereto.

I claim:

The ornamental design for a textile panel for a mattress cover, as shown and described.

In witness whereof, I hereunto subscribe my name this 8th day of April, 1931.

CHARLES LOFMAN.
